UNITED STATES PATENT OFFICE.

JOSEPH C. BARRETT, OF OCEANSIDE, NEW YORK, ASSIGNOR TO AJAX ELECTRIC HAMMER CORPORATION, OF NEW YORK, N. Y., A CORPORATION OF NEW YORK.

POWER-DRIVEN HAMMER OR RIVETER.

Application filed August 6, 1925. Serial No. 48,689.

This invention relates to power driven hammers or riveters and especially a hammer or riveter particularly adapted to electric or other rotary motor drive.

5 The object of the invention generally is a rotary motor driven hammer or riveter in which the rotary motion is converted into hammer or riveting thrusts with peculiar smoothness and efficiency in operation and 10 with marked freedom from shock to the operator and wear upon the hammer mechanism, and which is further characterized by its reliability in service, its durability and its ability to stand up under the severe service 15 operating conditions to which it is subjected.

To these ends I have devised a rotary driven power hammer including a double cam and rotary drive mechanism by which is effected a positive mechanical drive of the 20 hammer throughout the greater portion of the thrust stroke and with a gradually increasing acceleration of the hammer, but with a complete cessation of the mechanical drive and power connection during a definite 25 appreciable part of the cycle at the end of the thrust stroke, including the moment of impact, and whereby during the cessation of the mechanical drive the momentum of the hammer element carries the latter in advance 30 of the rotary drive to deliver the impact free from any driving or binding connection with the rotary drive and whereby the pick-up of the hammer element by the lagging rotary drive at the beginning of the lifting stroke 35 is effected in a sure and certain manner and without undue binding or strains upon any part of the mechanism, notwithstanding substantial variations in the length of the thrust stroke. My invention also includes a special 40 arrangement of thrust cam rotary drive and thrust roller guides whereby the gradual acceleration of the hammer during the thrust stroke is effected in a particularly efficient and effective manner.

45 For a better understanding of the above indicated features of the invention and others which will hereinafter appear, reference may be had to the accompanying drawings forming a part of this application wherein—

50 Fig. 1 is a side elevation of a hammer structure embodying my invention with a part of the casing removed,

Fig. 2 is a similar view thereof at right angles to Fig. 1;

Fig. 3 is a section along the line 3—3 of 55 Fig. 1,

Figs. 4—9 inclusive are diagrammatic views illustrating the functioning of the structure shown in Figs. 1 to 3, and

Fig. 10 is a diagrammatic view of a modified double cam structure.

Referring to the drawings where like numerals designate similar parts throughout, I have indicated my novel power hammer or riveter as comprising a main frame consisting of the casing part 1 which is adapted to receive a suitable power drive, as for example an electric motor (not shown for convenience in illustration), a part 2 containing the drive mechanism which is interposed between the power motor and the hammer, and a casing element 3 for guiding the hammer element 4 in its reciprocating movements. The casing parts 1 and 2 are preferably integrally formed of a single casting and a cover plate 2' for the part 2 is attachable to the frame part 2 by means of suitable bolts passing through the bolt holes 5. The rotary drive includes generally a rotary driving member or turret 6 which is journaled in the casing part 2, as for example by means of a ball bearing unit 7, the rotary member 6 being carried on the end of a shaft 6' and the latter being suitably journaled in the casing part 2. Between this rotary member 6 and the motor shaft 8 is interposed a suitable drive including a worm 9 on shaft 8 and a worm gear 10 carried by the rotary member 6. The casing part 2, 2' for the drive is adapted to contain a suitable lubricant and cover lids 11 are provided for inspection or introduction of the lubricant. The hammer element 4 is reciprocable in the direction of the arrow shown and carries integrally or rigidly therewith a slide block 12, the slide block 12 being laterally guided by the pair of thrust rollers 13, while the hammer head 4' is guided in any suitable manner, as for example within the chamber of casing part 3. The rotary drive member 6 is conveniently journaled so as to have its side surface approximately flush with or slightly below the face of the casing part 2 and the latter serves as a convenient seat for the slide block 12 which functions with

100 a driving crank pin 14 carried by the member 6 to effect reciprocation of the hammer element, the crank pin member 14 carrying

a rotary sleeve 14'. In the particular embodiment of my invention herein exhibited the rotary drive consists of a single rotary member 6 and pin 14, and the latter functions with a double cam carried by the slide block 12, and preferably integrally formed therewith, to effect the reciprocation of the hammer. This double cam includes a convex cam 15 and a concave cam 16, and on the withdrawal or lifting stroke of the hammer the rotating pin 14 is adapted to engage and follow the cam 15, while by engaging and following the other cam 16 the rotary drive imparts the thrust stroke to the hammer. The special construction and arrangement of the hammer and drive whereby I effect the hammering and riveting operation of the superior character indicated above, will be apparent upon reference to Figs. 4-9 inclusive, which figures are more or less diagrammatic and show the construction on a larger scale. Fig. 4 indicates the relative position of the parts of the mechanism during the lifting or withdrawing stroke of the hammer wherein the driving pin or roller 14 is in engagement with the lifting convex cam 15 and in a position to impart the maximum lifting or withdrawing speed to the hammer. After this maximum lifting speed is reached the speed of the driving crank pin 14 in the direction of the lift stroke begins to decrease and the hammer is gradually brought to rest by the retarding action of the cam 16 bearing against the roller pin 14. Fig. 5 indicates approximately the maximum lift position of the hammer with the driving pin 14 engaging the concave cam 16 to initiate the thrust stroke of the hammer, and Fig. 8 indicates the thrust stroke completed and the driving pin 14 initially engaging the convex cam to initiate the lifting stroke. The axis of rotation of the rotary drive member 6 is indicated at 17 and is preferably approximately in line with the centers of the thrust rollers 13. In the preferred embodiment illustrated both the cams 15 and 16 are of true arcuate form with their active and effective surfaces having a common center at 18, but it is understood that these cams may be of any suitable construction and especially that they may depart from the true arcuate form so long as they conform generally to that character. The word arcuate as used hereinafter is understood therefore to include all forms of the general character of the true arcuate construction, whether conforming exactly thereto or not. The arrangement is such that the center of revolution 18 of the cam surfaces is off-set laterally to one side of the axis 17 of the rotary member 6, and according to the embodiment herein exhibited a distance approximately equal to the radius of the circular path traveled by the center of the drive roller 14. For con-

venience I designate that part of the double cam which is functioning with the driving roller 14 at or near the end of the thrust stroke (Figs. 6-8) as the trailing or thrust end and at this end of the cams I have provided, in addition to an unimpeded opening or open space above the driving roller, a substantial lost motion or lateral play between the driving roller 14 and the cooperating cam surfaces 15 and 16 with which it alternately engages. For example, this lost motion or relative lateral play between the eccentric and the cams, as indicated in Fig. 8, is shown between the lines 19, the radius of curvature of the cam 16 being greater at this point than the sum of the corresponding radii of the cam 15 and the diameter of the driving roller pin 14, while, as indicated in Fig. 7, this lost motion or play is indicated by the distances between the lines 19' which are drawn on both sides of the driving roller. One purpose of this lost motion connection or lateral play and unimpeded opening or chamber above is to permit the hammer element and the slide block 12 to be carried forward a substantial distance in advance of the driving pin 14 when near the end of the thrust stroke without fouling or binding against the rotary pin 14 or any other part of the structure and to permit the pin to continue its arcuate path without binding in any practicable position the hammer may assume at the impact. For example, referring to Fig. 7, which indicates the probable approximate positions of the hammer mechanism at the initial impact, the lost motion or play indicated between the lines 19' on both sides of the driver 14 has permitted the hammer element to be carried forward in advance of the moving driving roller, and permits the latter to continue its arcuate path to pick up the hammer without binding against the cam 16 in the event that the hammer element 4 is not permitted to continue throughout its complete thrust stroke, as for example on meeting some obstruction. The relative arrangement of the rotary drive member 6, the driving roller 14 and the double cam must be such that at the beginning of the lifting stroke the eccentric 14 engages the curved surface of the cam 15 at a point and with the thrust in such direction as to impart to the hammer a force with a lifting component. The lost motion connection above referred to and the particular construction and relative arrangement of cam surface 15 effect this purpose. For example as indicated in Figs. 7 and 8, the driver 14 is free to advance through its arcuate path without binding the cam 16 while the hammer element is resting at the end of the thrust stroke, and engages the cam 15 at the initial lifting movement at a point where the tangent to the cam surface forms 70 80 85 90 95 100 105 110 115 120 125 130

less than a right angle with the horizontal, the driving pin 14 being permitted to engage the cam 15 at a point low enough to effect not only a lateral thrust but a lifting component with the hammer in its furthestmost thrust position. I have indicated at 20 the tangent as being drawn at approximately the point of the initial lifting engagement. This is the approximate point 5 of initial lifting engagement at the end of the maximum thrust stroke, but of course this point would be advanced further underneath the lifting cam 15 if the hammer should, at that instant, be slightly withdrawn 10 from the impact object, as for example in the position shown in Fig. 7. The construction and arrangement of the mechanism is also such that the side thrust of the driving pin 14 is always approximately 20 in the direction of a thrust roller 13, and particularly the arrangement of the cam 16, the driving eccentric and the thrust roller 13 adjacent thereto is such that beginning with the initial thrust stroke movement indicated in Fig. 5, for every unit movement 25 of the driving pin 14 about its arcuate path there is a corresponding linear thrust movement of the hammer which gradually increases towards the end of the thrust stroke. 30 For example in the particular embodiment of the invention herein exhibited, starting with a substantially zero linear thrust movement of the hammer for a unit arcuate movement of the center of the driving pin 14 at 35 the position indicated in Fig. 5, this linear thrust movement of the hammer gradually increases until the corresponding thrust movement or speed of the hammer approaching the end of the thrust stroke is considerably more than the linear component of the 40 speed of the center of the driving roller 14 in the direction of thrust, and in the particular embodiment herein exhibited, the hammer speed increases to a point where it is more than twice such speed of the driving 45 roller. In the preferred arrangement, this maximum speed of the hammer in the thrust direction is attained just prior to the driver 14 reaching a position substantially in line 50 with its center of movement and the adjacent thrust roller 13, the exact relative positions varying, of course, with the different relative arrangements of driving mechanism. I have roughly indicated such position in Fig. 55 6 where the driver 14 is just approaching its maximum linear speed in the direction of thrust, and the cam 16 on one side and the straight side of the slide block 12 on the other side are being squeezed between 60 the driver and the adjacent thrust roller 13, theta (θ) indicating the angle between the side of the guide block 12 and the tangent to the cam 16 at the point where the driver 14 engages therewith. The gradually increasing 65 speed of the hammer in the thrust di- rection, as the driver 14 rides up the concave cam 16, up to the point where its speed is greater than the linear component of the driver 14 in the thrust direction, results in the advance of the hammer by reason of its own momentum forward and ahead of the driver 14 when approaching the end of the stroke, so that in some such position as that indicated roughly in Fig. 6 the hammer 70 is carried forward by its own momentum to effect the impact of the hammer entirely free of the rotary drive, the double cam being constructed and arranged as above described to clear the driver when impact occurs. This arrangement while permitting 75 the free and unhindered independent forward and variable movements of the hammer with reference to the driving mechanism does not impair the positive mechanical driving connections during both the lifting and 80 the thrust strokes, so that a particular advantage of my power hammer is that while I effect the positive mechanical driving connection between the rotary eccentric and the hammer during the forward and backward 85 strokes, yet at an appreciable time before the actual impact of the hammer and during a considerable period thereafter in each cycle of operation there is no mechanical or binding connection between the hammer element 90 and the rotary drive. This insures the reduction to a minimum of shocks, vibrations and wear, and moreover the easy unbinding, pick up after each hammer stroke, the easy and gradual lift and reversal at the end of 95 the lifting stroke and the generally smooth operation contribute to endurance and reliability in operation. Fig. 9 indicates the essential active parts in this embodiment of the cams 15 and 16 at the trailing or thrust end thereof, namely those parts with which the driver 14 actually engages during operation. That part of the cam 16 above the line 21 appears to be active only at low speeds (starting and stopping), it being 100 found in practice that substantially no wear occurs on that part, indicating that at high speeds the hammer moves ahead of and out of engagement with the driving roller 14 when the latter reaches this point of the 105 cycle. 110 In the particular embodiment shown the relative lost motion or play between the driving eccentric and the double cam continues throughout the active portions of 120 both cams, this being desirable for practical constructional reasons, but it is understood that at the ends of the double cam corresponding to the lifting stroke of the hammer, such lost motion connection may be 125 eliminated. Some such arrangement as this is indicated in Fig. 10 where the cams 15' and 16' are just far enough apart at this end to accommodate the driving roller pin 14, but gradually diverge to effect the lat- 130

eral play or lost motion connection at the other ends of the double cam.

Also in the particular embodiment herein shown the convex cam 15 is in the form of 5 a revoluble ring which is journaled to rotate on the stud 15' carried by the slide block.

I claim:

1. In a power hammer, a power drive including a rotary drive member adapted to follow a fixed circular path, a reciprocable hammer member including a double concave-convex cam with which said rotary member alternately engages for reciprocating said hammer in opposite directions, and said cam having a connection with the rotary drive member at that part of the cycle just before the drive reaches its maximum speed in the direction of thrust which permits 10 the hammer to move forward independently of the rotary drive to deliver the impact and permits the rotary drive to follow through its arcuate path out of contact with the thrust cam to engage the lift cam at a 15 point where the tangent to this cam at the contact point makes less than a right angle with the line normal to the direction of reciprocation and pick up the hammer from its impact position.
2. In a power hammer, a power drive including a rotary drive member which is adapted to follow a fixed circular path, a reciprocable hammer member including a concave and a convex cam of arcuate form 20 which are spaced from each other to accommodate therebetween said rotary drive member, the centers of the surfaces of said cams being off-set laterally to one side of the center of movement of said rotary drive member, and said cams terminating at one end 25 into a lost motion connection with the rotary drive member which permits longitudinal movement of the hammer independently of the rotary drive just before impact and the 30 rotary movement of the drive member through its arcuate path free of the thrust cam to engage the lift cam at a point where

the tangent to this cam at the contact point makes less than a right angle with the line 35 normal to the direction of reciprocation and pick up the hammer after the impact.

3. A power hammer of the character set forth in claim 2 wherein the double cams are spaced apart throughout the effective part 40 of their length by a distance slightly greater than the diameter of the operating part of 45 the rotary drive member.

4. A hammer of the character set forth in claim 2 wherein both arcuate cams have the 50 centers of their surfaces coincident and said coincident center is off-set laterally from the central line passing through the center of movement of the rotary member, a distance 55 approximately equal to the radius of movement of the rotary member.

5. A hammer of the character set forth in claim 2 wherein the surfaces of the cams have centers which are coincident and wherein in a pair of oppositely disposed side thrust 60 rollers is mounted substantially in line with 65 said coincident centers.

6. A hammer of the character set forth in claim 2 wherein the convex cam is in the form of a circular ring which is rotatably mounted on the hammer element.

7. In a power hammer of the character set forth in claim 5 wherein the reciprocating hammer member is provided with parallel straight sides opposite the concavo-convex cam structure, together with a pair of 70 thrust rollers engaging said parallel straight sides.

8. In a power hammer of the character set forth in claim 5 wherein the hammer member is provided with a straight edge parallel to the direction of reciprocation on one side opposite the concavo-convex cam structure, together with a thrust roller engaging said straight edge and disposed approximately in line with the thrust of the rotary drive 80 member while the latter engages the cam.

In testimony whereof, I have signed my name to this specification.

JOSEPH C. BARRETT.

CERTIFICATE OF CORRECTION.

Patent No. 1,654,571.

Granted January 3, 1928, to

JOSEPH C. BARRETT.

It is hereby certified that error appears in the printed specification of the above numbered patent requiring correction as follows: Page 4, line 77, claim 7, and line 84, claim 8, for the numeral "5" read "1"; and that the said Letters Patent should be read with these corrections therein that the same may conform to the record of the case in the Patent Office.

Signed and sealed this 14th day of February, A. D. 1928.

Seal.

M. J. Moore,
Acting Commissioner of Patents.
